UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,424,917.

Specification of Letters Patent. Patented Aug. 8, 1922.

Application filed November 16, 1921. Serial No. 515,454.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 This invention relates more particularly to an arrangement such as covered by my prior Letters Patent No. 1,347,638, wherein the storage magazine is provided with a permanent matrix locking device which may 15 be instantly moved to active or inactive position at will, and which is arranged to control a magazine locking device in such manner as to permit and prevent the removal of the magazine as the matrices are locked and 20 unlocked, respectively. The present invention is directed to certain improvements which are intended to simplify the construction and operation of the patented structure. These improvements will best be understood 25 from the detailed description to follow.

Referring to the drawings:

Fig. 1 is a top plan view of the lower section of a linotype magazine equipped with my improvements, certain of the parts being 30 broken away to show the interior construction and arrangement;

Fig. 2 is a section taken on the line 2—2 of Fig. 1, and showing the matrix locking bar in inactive position;

35 Fig. 3 is a similar view but showing the matrix locking bar in its active position;

Fig. 4 is a section taken on the line 4—4 of Fig. 1;

40 Fig. 5 is a vertical section, on an enlarged scale, taken through the lower end of the magazine;

Fig. 6 is a similar view, but showing the matrix locking bar projected into the magazine; and

45 Fig. 7 is a section taken on the line 7—7 of Fig. 2.

The matrices X, stored in the channeled magazine A, are released therefrom one at a time by the escapements C, these latter being supported in the bar or frame C² (Figs. 50 5 and 6). The side plates of the magazine are formed on their inner faces with the op-

posing grooves A¹, wherein the projecting ears of the matrices engage, the upper magazine plate having the detachable reenforced 55 cover-section A², and the lower magazine plate having the openings A¹⁰ to receive the grooved positions of the escapement supporting bar C², all in the usual way.

As in my prior patent before mentioned, 60 the magazine is provided with a matrix locking bar E seated and enclosed within a corresponding groove A³ formed in the inner face of the detachable section A². Likewise, the bar E is adapted to be moved to its active 65 and inactive positions by shifting it longitudinally in opposite directions,—that is to say, when shifted toward the left, means are employed to project it sidewise into the magazine for locking the matrices therein, and when shifted toward the right, additional means are employed to withdraw it from the magazine for releasing the matrices. The first-mentioned means are substantially 70 the same as disclosed in the patented structure, consisting of a plurality of buttons or protuberances A⁷ carried by the magazine section A² and adapted to cooperate with

corresponding recesses or depressions E² formed in the upper side of the bar. In the 80 present instance, however, the depressions E² are somewhat larger than those shown in the patent, presenting flat bottom surfaces extending parallel to the longitudinal axis of the bar, for reasons which will later appear. In the patent, the second mentioned 85 means are in the form of leaf springs suitably arranged for the purpose stated; but, in the present arrangement, these springs are done away with and are replaced by a set 90

of cam devices which act positively to withdraw the bar from the magazine as it is shifted to the right. In the embodiment shown, such cam devices are made up, on the one hand, of a pair of headed pins E¹ 95 extended upwardly from the bar E and secured thereto in any suitable manner, and, on the other hand, of a pair of cam plates A⁴ detachably secured to the magazine section A² and formed with longitudinally arranged slots A⁵ wherein the pins E¹ are slidably arranged, it being noted that the cam plates A⁴ are also formed with tracks or ways A⁶ upon which the heads of the

pins E^1 are adapted to slide. In this connection, it is pointed out that the lower depressed portions of the tracks A^6 are straight and extend parallel to the longitudinal axis 5 of the bar E .

The action of the parts will now be clear: When the bar E is in its inactive position, as shown in Figs. 1 and 2, the heads of the pins E^1 rest upon the upper flat surfaces of 10 the cam plates A^4 , which thus support the bar in a raised condition and out of the path of the matrices (Figs. 5 and 7), the protuberances A^7 at this time being engaged with the flat bottom surfaces of the depressions E^2 . If now the bar be shifted to the 15 left, its initial movement (which is a longitudinal one only, as permitted by the flat bottom surfaces of the depressions E^2) disengages the heads of the pins E^1 from the upper surfaces of the cam plates A^4 and 20 brings them to the inclined positions of the tracks A^6 . This initial movement of the bar simultaneously brings the curved walls of the depressions E^2 into engagement with the 25 protuberances A^7 , which then act, by the continued movement of the bar, to displace it sidewise into the magazine (Fig. 6). The heads of the pins E^1 during such displacement slide along the tracks A^6 and finally 30 run onto the straight parallel portions thereof, when further sidewise displacement of the bar is prevented. The final movement of the bar (which is also a longitudinal one only, as permitted by the straight parallel 35 portions of the tracks A^6) disengages the depressions E^2 entirely from the protuberances A^7 and cause the latter to engage the straight upper side of the bar, thereby maintaining the bar firmly and securely in its locking 40 position, see Fig. 3. Conversely, when the bar is shifted to the right, its first movement (which is a longitudinal one only) brings the recesses E^2 in position to receive the protuberances A^7 and at the same time carries 45 the heads of the pins E^1 into engagement with the inclined portions of the tracks A^6 ; its further movement then causes the heads of the pins E^1 to climb up the inclined portions 50 of the tracks A^6 so as to lift the bar from the magazine, the protuberances A^7 descending along the curved sloping walls of the depressions E^2 until they become engaged with the flat bottom surfaces thereof; and its final movement (which is also a longitudinal one only) then slides the heads of 55 the pins E^1 onto the flat upper surfaces of the cam plates A^4 , in which condition of the parts, the bar is maintained firmly and securely in its unlocking position.

60 In these machines, before removing the magazines, it is desirable to push the matrices back up within the same to disengage them from the escapements. In my prior patent, this result was accomplished by moving the locking bar edgewise rearwardly of

the magazine, but, in the present instance, such edgewise movement of the bar and consequently the means employed for producing it are dispensed with. In lieu thereof, and as shown in Figs. 5 to 7, the bar E is formed 70 on its rear edge with a beveled surface E^3 extending continuously along the bar from one end to the other. According to this construction, when the bar E is projected into the magazine in the manner previously described, the beveled surface E^3 engages the upper ears of the lowermost matrices and pushes them rearwardly out of engagement 75 with the escapements C (see Fig. 6). Of course, when the bar is subsequently withdrawn from the magazine, the matrices are allowed to slide downwardly in the magazine and again come under the control of the escapements (Fig. 5).

To insure the retention of the bar E in its 80 different terminal positions, there is employed a safety catch or dog (Figs. 1 to 4) slidably connected to the magazine section A^2 by the pin-and-slot devices F^1 and formed with a rectangular opening F^2 through 85 which the bar passes. A spring F^3 , pressing upwardly on a turned over part of the catch, serves to engage the lower wall of the opening F^2 in one or the other of two transverse notches E^7 formed on the underside of the 90 bar E . As will be apparent, the bar is free to be shifted in either direction by simply pressing downwardly on the catch, which will then snap back into the appropriate notch E^7 as the bar assumes one or the other 95 of its terminal positions. It may be noted that the bar is formed with an upstanding handle E^8 which is located immediately adjacent the catch F , so that the parts may be 100 easily and quickly manipulated.

Having thus described my invention, what I claim is:—

1. A linotype magazine provided with a matrix locking bar shiftable longitudinally in opposite directions, means for projecting the bar into the magazine as it is shifted in one direction and positively-acting means for withdrawing the bar from the magazine as it is shifted in the opposite direction.

2. A linotype magazine provided with a matrix locking bar shiftable longitudinally in opposite directions, and two sets of cam devices formed partly on the magazine and partly on the locking bar, one set acting as the bar is shifted in one direction to project it into the magazine, and the other set acting as the bar is shifted in the opposite direction to withdraw it from the magazine.

3. A magazine as specified in claim 2, characterized by the fact that the cam devices therein recited are so constructed and arranged as to permit a slight independent longitudinal movement of the matrix locking bar in each of its terminal positions,

so that the control of the bar may be transferred from one set of cam devices to the other and vice versa.

4. The magazine A formed with the 5 transverse groove A³, the longitudinally shiftable matrix locking bar E located in said groove and formed in its upper side with the recesses or depressions E², the buttons or protuberances A⁷ arranged to cooperate with said recesses, the headed pins E¹ attached to the locking bar, and the slotted cam plates A⁴ cooperating with said pins, substantially in the manner shown and described.
- 15 5. A linotype magazine provided with a matrix locking bar shiftable longitudinally in opposite directions and formed at one side with a pair of transverse notches, a locking plate formed with an opening 20 through which the bar extends, and a spring acting on the plate and serving to engage a wall of its opening in one or the other of the bar notches.
- 25 6. A linotype magazine provided with a matrix locking bar movable bodily into the

magazine, the said bar being formed along its rear edge with a continuous beveled surface adapted to engage and push back the matrices within the magazine.

7. A linotype magazine provided with a 30 matrix locking bar shiftable longitudinally thereon, and means for projecting the bar sidewise into the magazine as it is shifted longitudinally, the said bar being formed along its rear edge with a beveled surface 35 adapted to engage the matrices as the bar is projected into the magazine and push them rearwardly.

8. The linotype magazine A formed with the transverse groove A³, the longitudinally 40 shiftable matrix locking bar E located in said groove and formed along its rear edge with the beveled surface E³, and means (such as the depressions E² and the protuberances A⁷) for projecting the bar into 45 the magazine as it is shifted longitudinally.

In testimony whereof, I have affixed my signature hereto.

DAVID S. KENNEDY.
